TURNTABLE AND MOUNTING THEREFOR

Fred G. Manly, Chicago, Ill.

Application January 16, 1941, Serial No. 374,606

7 Claims. (Cl. 212—68)

The present invention relates to a novel turntable and more particularly to one adapted for anti-friction mounting at its periphery.

Turntables are usually constructed for mounting at their centers, such a mounting usually constituting the means through which driving rotation is effected. This construction necessarily limits the effectiveness of the turntable in carrying heavy loads due to the unsupported weight from its center to its periphery. Furthermore, power takeoff for other mechanisms is restricted to the centrally located shaft driving the turntable. By locating the driving mechanism centrally of the turntable, control mechanisms must necessarily be placed beyond the turntable periphery in exposed, unsightly positions.

It is, therefore, an important object of this invention to provide a turntable construction mounted for rotation at its periphery whereby control mechanisms or separate power drives are effective through its axis of rotation.

Another object of the present invention is the provision of a turntable construction having driving means therefor adjacent its periphery.

A further object of the present invention is the provision of a turntable construction capable of rotatably supporting heavy loads at any position across its face.

A still further object of the present invention is the provision of a turntable construction being so mounted as to minimize deflections when subjected to heavy loads.

Another and still further object of the present invention is the provision of a turntable construction having an anti-friction peripheral mounting constantly operating in lubricant and sealed against the entrance of foreign matter.

A further object of this invention is the provision of a turntable which is simple in construction, durable and efficient in use, and which may be readily assembled and disassembled.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawings, in which:

Figure 1 is a view, partially in top plan elevation and partially in horizontal section, taken substantially along the plane indicated by the line I—I of Figure 4 and illustrating a turntable

constructed in accordance with the principles of the present invention;

Figure 2 is a side-elevational view illustrating one use for the turntable construction of the present invention, in which a swinging crane is applied to it and the table and crane mounted on a tractor;

Figure 3 is an enlarged vertical cross-sectional view, with parts in elevation, taken substantially in the plane indicated by the line III—III of Figure 1; and,

Figure 4 is an enlarged vertical cross-sectional view, with parts in elevation, taken substantially in the plane indicated by the line IV—IV of Figure 1 at an angle of 90° to the section plane of Figure 3.

In Figure 2 there is illustrated a tractor 10 carrying a swinging crane 11 by means of a turntable construction 12 embodying the principles of the present invention.

As best shown in Figures 1, 3 and 4, the turntable construction 12 generally comprises an inner rotating member 13, an outer stationary supporting member 14, and a plurality of anti-friction members 15 interposed therebetween.

The inner rotating member 13 is generally circular in shape (Figure 1) of flat metal having its peripheral portions 16 formed inverted U-shape in vertical cross section, as shown in Figures 3 and 4, for a purpose to be more fully explained hereinafter.

The outer edge of the rotating member 13 is formed as a thick rim 17 and is provided centrally of its outer surface with a load-carrying raceway 18.

A ring gear 19 is inserted within the U-shaped portions 16 to seat against the inside face of the rim 17 and is maintained in mounted position by a plurality of cap screws 20 (Figures 1, 3 and 4).

It is to be noted that the rim 17 and the adjacent leg 21, forming the inverted U-shaped portion 16 provide strength along the direction of the rotating axis to minimize deflections in the rotating member 13 when rotated under load.

The centrally located web portion 22, connecting the inverted U-shaped peripheral portions of the rotating member 13, is provided with as many openings 23 as are necessary to properly balance the member for rotation. If desired a central aperture 24 may be provided to allow control or additional driving mechanisms to be inserted therethrough which would be unaffected by the rotation of the member 13. As illustrated in Figures 3 and 4, a driving mechanism 25 may be inserted through the opening 24 for driving a

mechanism such as the swinging crane 11 illustrated in Figure 2. It is to be understood, however, that the turntable construction embodying the principles of this invention is not to be confined only to use with swinging cranes as the turntable illustrated herein may be used wherever loads are to be rotated by power. Furthermore, control rods or other mechanisms (not shown) may be substituted for the driving mechanism 25, or, the aperture 24 may be enlarged to include therethrough both types of mechanisms.

The stationary supporting member 14 comprises a lower member 26 being held in stationary supporting position by channel-shaped members 27 and 28. The channel-shaped members are connected to the downwardly extending legs 29 of the supporting member 14 by means of bolt and nut assemblies 30 (Figure 3). If desired, the channel-shaped members 27 and 28 may be formed as integral portions of the supporting member 26.

The supporting member 26 is generally U-shaped in cross section having a rim portion 31 of such diameter as to receive within and adjacent thereto in closely spaced relation the inner rotating member 13. A web portion 32 connects the rim portions 31 and is shaped to provide the downwardly extending integral legs 29. Like the web of the inner rotating member 13, the web 32 may also be provided with a central aperture 33 for receiving therethrough control or driving mechanisms, or the like. In the present instance, a driving mechanism in the form of a bevel gear 34 is illustrated as extending through the aperture 33.

A plurality of bosses 35, 36 and 37 are provided on the web 32 to which are connected a driving mechanism 38, bolted or attached by other suitable means (not shown), which is not described herein as it forms no part of the present invention.

A pinion 39 is driven by the driving mechanism 38 and positioned within the inverted U-shaped portion 16 in a manner to have toothed engagement with the ring gear 19. Rotation of the pinion 39 serves to drive the inner rotating member 13, as shown in Figures 1 and 4.

Suitable openings 40 are also provided in the member 26 through which excess lubricant, dirt or the like may drain.

An upper member 41 of the stationary supporting member 14 is formed as a cap ring having a downwardly extending leg 42 of the same thickness and diameter as the rim 31 of the lower supporting member 26. The adjacent surfaces of the rim portions of the lower supporting member 26 and of the upper member 41 are of stepped configuration as shown in the drawings. This stepped configuration provides mating shoulders 41a, and the resulting male and female joint assures the same alignment between the members whenever they are connected together. The cap ring 41 is connected to the rim 31 by means of a plurality of cap screws 43.

When the ring 41 is connected to the lower supporting member 26, a load-carrying raceway 44 is provided centrally of the connection therebetween to register with the raceway 18 provided in the rim of the inner rotating member 13 when the latter and the outer member 14 are positioned as shown in Figures 3 and 4. It will be apparent that the male and female joint between the members is necessary to assure proper alignment of

the surfaces of the raceway 44 whenever the members are connected by the cap screws 43.

As shown in Figure 1, a plurality of spherical balls or anti-friction members 15 are interposed between the registered raceways to floatingly support the inner rotating member 13 on and within the outer stationary supporting member 14. A seal 45 of leather, fabric or similar material is inserted within a suitable circumferentially extending slot provided on the under side of the inwardly extending leg 46 of the cap ring 41. A similar seal 47 is provided between the inner rotating member 13 and the stationary supporting member 26. The leather seals 45 and 47 serve to isolate the anti-friction members 15 in a manner to seal lubricant confined within the space provided between the inner member 13 and the outer member 14 and further seals the anti-friction members from foreign matter.

It will be observed from the foregoing description that the present invention provides a novel turntable construction having a rotatable anti-friction mounting at its periphery for more efficiently and properly supporting loads whereby deflections are reduced to a minimum. Furthermore, the construction permits other mechanisms, such for example as controls and additional power drives, to be located and operated through the central portion of the turntable without affecting its rotation.

While a particular embodiment only of this invention has been illustrated, it will, of course, be understood that the invention should not be limited thereto since many modifications may be made and, therefore, it is contemplated by the appended claims to cover all such modifications as fall within the true spirit and scope of the present invention.

I claim as my invention:

40. 1. A turntable construction comprising a rotatable member having a raceway in the outer periphery thereof, a stationary supporting member of U-shaped section surrounding the peripheral marginal edges of said rotatable member in concentric spaced relation thereto and having a raceway in the inner periphery thereof adapted to register with the raceway in the rotatable member, anti-friction bearing elements in said raceways for maintaining the members in said spaced relation, and means between the marginal edges of said rotatable member and the adjacent portions of the U-shaped section of the stationary member for sealing the space between the members.

55. 2. A turntable construction comprising a rotatable member having a raceway in the outer periphery thereof, a stationary supporting member of L-shaped section surrounding said rotatable member in concentric spaced relation thereto, one leg of said section being spaced from a marginal edge of said rotatable member and the other leg of said section being spaced from the outer periphery of said rotatable member, a ring member of L-shaped section detachably secured to said supporting member, one leg of said ring member being spaced from a marginal edge of said rotatable member opposite to the first mentioned marginal edge and the other leg of said ring member being seated on said other leg of the supporting member, a raceway in said other legs of the ring member and the supporting member adapted to register with the raceway in the rotatable member, and anti-friction ball bearing elements in said raceways for maintaining the rotatable member and the supporting member

and the connected ring member in said spaced relation.

3. A turntable construction comprising a rotatable load-carrying member having a circumferentially extending inverted U-shaped portion at its periphery, the outer flange of said U-shaped portion forming a rim having a load-carrying raceway on the outer side thereof, a ring gear on the inner side of said rim through which said load-carrying member is driven, a stationary member having a circumferentially extending U-shaped portion at its periphery adjacent to and in spaced relation from said rim, the legs on the U-shaped portion of the stationary member overlapping opposite marginal edge portions of said rim, the web on the U-shaped portion of the stationary member having a load-carrying raceway on its inner side in registry with the raceway on said rim, and a plurality of anti-friction members disposed in said registered raceways.

4. A turntable construction comprising a rotatable circular load-carrying member having a circumferentially extending inverted U-shaped portion at its periphery for receiving a driving member therein, said load-carrying member having at least one opening therethrough for surrounding mechanisms unaffected by rotation of said member, an axially extending rim flange forming the outer edge of said U-shaped portion having a load-carrying raceway on its outer side, a ring gear on the inner side of said rim whereby said load-carrying member is rotated by said driving member, a stationary supporting member having a U-shaped circumferentially extending peripheral portion embracing the marginal edges of said rim in adjacent spaced relation therefrom, said supporting member including an upper and a lower member, said lower member having an L-shaped portion embracing the lower portion of said rim and terminating adjacent the radial axis of said load-carrying raceway on said rim, said upper member being L-shaped in section and embracing the upper portion of said rim, means for connecting said upper and lower supporting members, said supporting member having a load-carrying raceway formed at the connection between said upper and lower members, a plurality of spherical balls disposed in said raceways, and sealing means between said load-carrying member and said supporting member for isolating said spherical balls and retaining lubricant within the space between said members.

5. A turntable construction comprising a rotat-

able member having a raceway in the outer periphery thereof, a stationary supporting member of U-shaped section surrounding the peripheral marginal edges of said rotatable member in concentric spaced relation thereto and having a raceway in the inner periphery thereof adapted to register with the raceway in the rotatable member, anti-friction bearing elements in said raceway for maintaining the members in said spaced relation, said U-shaped section of the supporting member being split through the annular raceway therein and radially with respect to said rotatable member to provide ring portions each having axially spaced surfaces connected by a shoulder intermediate the inner and outer peripheries of the ring portion, means for clamping said ring portions together whereby the split surfaces and shoulders thereon seat against each other to align the split surfaces of the annular raceway therein, and means between the marginal edges of said rotatable member and the adjacent portions of the U-shaped section of the supporting member for sealing the space between the members.

6. A turntable construction comprising a member having an annular raceway in the outer periphery thereof, a member with a ring portion surrounding the periphery of said first member and having an annular raceway in the inner periphery thereof aligned with said first annular raceway, anti-friction bearing elements in said raceways for maintaining said members in spaced relation and movable relative to each other, said ring portion of the second member being split through the raceway therein radially with respect to said first member to provide mating male and female portions, and means for clamping said split ring portion whereby the mating male and female portions coact to align the adjacent surfaces of the split raceway.

7. An outer raceway for a turntable construction comprising a ring shaped member having an annular raceway in the inner periphery thereof, said ring shaped member being split radially through said annular raceway to provide ring portions each having axially spaced surfaces connected by a shoulder intermediate the inner and outer peripheries of the ring portion, and said ring shaped member also having internally threaded openings extending axially thereof for receiving studs for connecting the ring portions together whereby the split surfaces and shoulders thereon seat against each other to align the split surfaces of the annular raceway.

FRED G. MANLY.
